UNITED STATES PATENT OFFICE.

BENJAMIN F. VAN CAMP, OF WARSAW, INDIANA, ASSIGNOR, BY MESNE ASSIGNMENTS, TO INDIANA BURIAL VAULT COMPANY, OF INDIANAPOLIS, INDIANA, A CORPORATION OF INDIANA.

BURIAL-VAULT.

SPECIFICATION forming part of Letters Patent No. 728,337, dated May 19, 1903.

Application filed February 3, 1902. Serial No. 92,454. (No model.)

To all whom it may concern:

Be it known that I, BENJAMIN F. VAN CAMP, a citizen of the United States, residing at Warsaw, in the county of Kosciusko and State of Indiana, have invented a new and useful Burial-Vault, of which the following is a specification.

My present invention relates to a novel sarcophagus or burial-vault, and has for its object to simplify and improve the construction disclosed in Letters Patent No. 597,625, issued to me January 18, 1898. In said patent is disclosed a vault composed of a number of separate molded sections of plastic material, said sections being strengthened by metallic frames embedded therein.

The objects of my invention, stated more specifically, are to eliminate certain of these embedded frames without weakening the slabs or sections; to provide a novel form of joint between the sections, said joints being calculated to strengthen the structure at those points where the slabs or sections abut; to construct the cover-sections in a manner to provide against possible injury to the cover-frames when the cover-sections or slabs are piled one upon another for storage or transportation; to strengthen the various slabs by metallic frames arranged exterior thereto, so that the contraction and expansion of said frames will not effect the checking or cracking of the plastic material, and, finally, to provide simple and efficient locking mechanism which will automatically lock the cover-sections in place when the latter have been lowered upon the vault, the various structural features being devised with a view to producing a vault which will be absolutely air and water tight and burglar-proof.

To the accomplishment of these objects and others subordinate thereto, all as will herein-after more fully appear, the invention in its preferred embodiment comprehends that construction and arrangement to be hereinafter described, illustrated in the accompanying drawings, and succinctly defined in the appended claims.

In said drawings, Figure 1 is a perspective view of my vault complete, parts being broken

away to better disclose the construction. Fig. 50 2 is a longitudinal vertical section on the line 2 2 of Fig. 4. Fig. 3 is a horizontal sectional view on the line 3 3 of Fig. 4. Fig. 4 is a transverse sectional view on the line 4 4 of Fig. 2. Fig. 5 is a detail perspective view of 55 one of the cover-frames, and Fig. 6 is a detail view illustrating the manner in which the bolts for securing the locking-strips are secured in the plastic material. Fig. 7 is a detail view of one of the vault-sections or 60 slabs, showing the metallic binding-frame extending continuously around and seated in the edges of the section.

Like numerals of reference are employed to designate corresponding parts throughout the 65 views.

The vault, like that described in my patent aforesaid, is composed of a plurality of sections which when assembled form a covered receptacle for the reception of a casket. 70 The bottom is composed of three sections or slabs 1, 2, and 3, and its outer edge is rabbed, as indicated at 4, to receive the lower edges of side sections or slabs 5, 6, 7, and 8 and end sections or slabs 9 and 10, the end 75 edges of the side walls of the vault being rabbed, as indicated at 11, (see Fig. 3,) to accommodate the side edges of the end slabs 9 and 10.

Thus far the construction is not materially 80 different from that disclosed in the patent; but it will be noted that the manner of forming the joints between the meeting edges of the slabs or sections is distinctly different in the present instance and is vastly superior to 85 the means employed heretofore. The opposed faces of the joints instead of being brought substantially flush are disposed in divergent relation, the divergence being outward to permit the interposition of cement or other 90 bonding material 12, which at the corners and sides of the vault is extended beyond the joint proper to form a heavy strengthening-rib 13, molded within a transversely-curved casing 14, which extends the full 95 length of the joint. This casing, which may be designated a "joint-strip," may be permitted to remain after the joint has been

molded or may be removed. In either event the quantity of bonding material employed in forming the joint serves to make the structure even stronger than if the vault were 5 formed in a single cast or molding.

While, as heretofore stated, I have found it undesirable to embed metallic frames in the plastic slabs, I nevertheless consider it desirable to strengthen the slabs by means of 10 a metallic framework, which instead of being entirely embedded in the material is merely seated around the edges of each slab, so that the latter will not be checked or cracked by the contraction and expansion of 15 the metal after the vault has been exposed to heat or cold. These frames, which are indicated by 15, are merely strips of metal of substantially semicircular cross-sectional contour passed around the edges of a section or 20 slab and having their ends connected in any suitable manner, as by welding, riveting, or the like, it being observed that these binding-frames are retained in place not only by reason of their being inserted in the edges of 25 the slab, but also by the bonding inserted in the joints.

It has been stated that the opposed faces of the joints diverge outwardly, and while this is true in a majority of instances it should be 30 noted that the joints 16 and 17 in the bottom of the vault are exceptions to this rule and diverge inwardly.

The construction thus far described comprehends the vault or receptacle proper; but it 35 will be noted that an arched cover is provided for completely closing and sealing the vault after the casket has been deposited therein. This cover includes a plurality of sections, preferably three in number and indicated by 40 18, 19, and 20. Each cover-section is transversely arched and is composed of plastic material molded upon a metallic cover-frame comprising longitudinal frame members 21 and 22, to which are riveted or otherwise secured 45 the opposite ends of spaced arch-bars 23, each alternate arch-bar being provided with a tie-bar 24, secured at its opposite ends to the opposite sides of the arch-bar, at a slight distance above the extremities thereof. 50 This particular arrangement should be especially noted for the reason that this elevation of the tie-bars to a plane somewhat above the lower edges of the cover, permits the casket to extend somewhat higher than the side 55 walls of the vault, and thereby permits the vertical dimensions of the vault to be decreased somewhat. At each extremity of the cover the end tie-bar 25 of the terminal cover-section extends between the extreme ends of 60 the adjacent arch-bar, the contiguous extremities of this arch-bar, the tie-bar 25, and the longitudinal bars 21 and 22 being secured by a single rivet or bolt 26. (See Fig. 5.) The arch-bars of the cover-frames thus constructed 65 are embedded in the cover-sections; but the tie-bars 24 extend transversely across the dome of the arch, while the longitudinal

bars 21 and 22 and the terminal tie-bars 25 extend along the lower edges of the cover imposed upon the upper edges of the vault. 70

In my patented construction I employed cover-frames somewhat similar to those herein described; but I find in practice that the unbacked tie-bars are apt to become bent or broken or to cause cracking or checking of 75 the cover-sections when a number of such sections are piled one upon another for the purpose of storage or transportation. My present invention, therefore, contemplates the formation of backing-ribs 27 upon the inner side of the arch and depending to the tie-bars, these backing-ribs being preferably formed of plastic material and molded integral with the cover-sections. I have also found it desirable to form strengthening- 80 ribs 28 upon the under side of the cover-sections directly opposite or below such of the arch-bars as are not equipped with tie-bars, inasmuch as said arch-bars are designed to be employed for the retention of rings or handles 29 by means of which the cover-sections are lowered upon the vault. One other peculiarity of the cover-frames should be noted before we pass to a consideration of the cover-securing devices. By reference to Figs. 2 85 and 4 it will be noted that the joints 20 between the cover and the upper edges of the vault or receptacle are made outwardly flaring by reason of the beveling of the under edges of the cover-sections. For this reason 90 the longitudinal bars 21 and 22 of the cover-frames are given a slight angular disposition to accommodate them to the beveled edges of the cover.

The foregoing description is believed to be 105 complete so far as the construction of and the manner of assembling the various sections are concerned; but an additional feature of my invention involves a simple and effective locking device or a series of locking devices 110 which serve to automatically lock the cover-sections in place as soon as they have been lowered to place. These locking devices are in the form of cooperating catches 31 and 32, 115 carried by the cover and receptacle, respectively, and designed to interlock when brought into proper relative positions. The upper members 32 of these catches are bolted, riveted, or otherwise secured to the longitudinal bars 21 and 22 of the cover-frames and depend just within the side and end walls of the receptacle when the cover is mounted thereon. The catch members 31 are of spring form and constitute the upper ends of angle-braces 33, which extend down along the side 120 and end walls and are bent at their lower ends to form corner-brackets 34 at the lower inner corners of the receptacle. The engaging ends of the catch members are provided with engaging heads 35, having inclined faces 125 36, which engage one another and cause the members 31 to spring back, and thus permit the members 32 to move to their engaging positions. The angle-braces 33 are secured to 130

the walls of the receptacle by bolts 37, extended into the plastic material and provided with nuts 38, disposed against angular retaining-plates 39, embedded in the slabs, as 5 best shown in Fig. 6 of the drawings.

In conclusion, it may be stated that my vault is constructed of plastic material which is absolutely impervious to water, and the vault is therefore moisture-proof, as well as 10 secure against the inroads of evilly-disposed persons.

It is thought that from the foregoing the construction and many advantages of my vault will be clearly apparent; but while the 15 present embodiment of the invention is thought at this time to be preferable I wish to reserve the right to effect such changes, modifications, and variations of the illustrated structure as may be suggested by experience 20 and experiment and embraced within the scope of the protection prayed.

What I claim is—

1. A burial-vault comprising a receptacle and an arched cover, said cover being provided with transverse tie-bars extending 25 transversely across the arch thereof and with backing-ribs extending from the cover and constituting backings for the tie-bars.

2. A burial-vault comprising a receptacle 30 and an arched cover, said cover being provided with connected arch-bars embedded therein, tie-bars extending across the arch of the cover and secured to the arch-bars, and backing-ribs extending downwardly from the 35 cover and constituting backings for the tie-bars.

3. A burial-vault comprising a receptacle, an arched cover and a cover-frame, said cover-frame comprising longitudinal bars disposed 40 along the opposite sides of the cover, arch-bars extending between the longitudinal bars and embedded in the cover, and tie-bars retained by certain of the arch-bars and disposed in a plane above the horizontal bars of 45 the frame.

4. A burial-vault comprising a receptacle,

an arched cover, and a cover-frame comprising longitudinal bars extending along the opposite longitudinal edges of the cover, arch-bars extended between the longitudinal bars 50 and embedded in the cover, tie-bars located below the alternate arch-bars and secured thereto at points above the ends of the arch-bars, and backing-ribs extending downwardly from the cover and constituting backings for 55 the tie-bars.

5. A burial-vault composed of separate molded sections, and metallic binding-frames extending continuously around the sections and seated in the edges thereof. 60

6. A burial-vault comprising a receptacle and cover, said receptacle being provided with internal angle-braces secured to and lying against the side walls thereof and bent at their lower ends to form corner-brackets, laterally-yielding catch members formed at the upper ends of the angle-braces, and coöperating catch members depending from the cover and disposed to pass between the receptacle-walls and the yielding catch members 70 to engage the latter.

7. In a burial-vault, the combination with a receptacle and cover composed of plastic material, of a metallic strengthening-frame embedded in said cover, catch members secured to said frame and extended into the receptacle, and braces secured to the inner faces of the walls of the receptacle, said braces being bent at their lower ends to form corner-brackets located at the lower corners of the 80 receptacle and formed at their upper ends with spring catch members provided with heads disposed for engagement with the catch members extending from the cover. 75

In testimony that I claim the foregoing as 85 my own I have hereto affixed my signature in the presence of two witnesses.

BENJAMIN F. VAN CAMP.
